UNITED STATES PATENT OFFICE.

ARTHUR JACKSON WEST, OF BETHLEHEM, PENNSYLVANIA, ASSIGNOR TO BETHLEHEM STEEL COMPANY.

INTERNAL-COMBUSTION ENGINE.

Application filed April 28, 1924. Serial No. 709,370.

My invention, which is a continuation in part of application No. 422,753, filed Nov. 9, 1920, and since matured into Re-issue Patent No. 16,909, March 20, 1928, relates to cooling devices for internal combustion engines and it has for an object to provide apparatus of this character which shall be reliable in operation and which shall assure that cooling water shall not be come admixed with oil in the engine casing.

To cool the interior parts of an internal combustion engine, such as a piston, necessitates movable piping, which, in turn, requires articulated or telescopic joints. With an engine of this type, it is desirable to have a closed casing in order to prevent loss or contamination of oil. Also the conduit means must be of such a character to avoid the admixture of cooling water with the engine oil. Hence, I use telescopic piping connections providing for the inlet and outlet of cooling water to an engine piston, the telescopic connections being arranged within the engine casing; and each connection is provided with a communicating conduit leading through the engine casing, suitable packing being arranged between the conduits and the casing to prevent the escape of oil. It is an object of my invention to provide apparatus of this character which shall include a lower piping member terminating within and at the bottom of a pocket or box-like member protruding inwardly of the engine casing and open at one side through the wall of the engine casing, such lower piping member being arranged to receive an upper piping member connected to a piston and the upper piping member passing through the top of the box or pocket member, across the latter, and telescoping with the lower piping member, whereby water passing along the outside of the upper piping member may collect in the pocket.

A further object of my invention is to provide a telescopic piping connection wherein the outer pipe member terminates within a pocket or casing and the cooperating pipe member extends across the casing and enters the first piping member, packing being arranged between the cooperating pipe members and an adjustable packing device being carried by the pocket or box member and cooperating with the second pipe member, whereby the passage of fluid

outside of and along the second piping member beyond the box or pocket member is prevented.

These and other objects are accomplished by my invention as will be apparent from the following description taken in connection with the accompanying drawings, forming a part of this application, in which:

Fig. 1 is a fragmentary view, partly in section, showing my improved cooling arrangement applied to an engine;

Fig. 2 is a fragmentary detail view of one of the cooling devices; and,

Fig. 3 is a detail sectional view on a larger scale showing my improved type of telescopic connections.

Referring now to the drawings for a better understanding of my invention, in Fig. 1, I show an engine at 10 having a cylinder 11 within which fits a piston 12. The piston 12 is provided with an inlet cooling connection 13 and an outlet cooling connection 13^a.

The cooling connections 13 and 13^a are identical in structure so that the description of one is sufficient for the purposes of my invention. Each cooling connection includes a lower pipe member 14 joined to a conduit 15 passing through the engine casing 16, a packed joint 17 surrounding the conduit to prevent leakage. The upper end of the pipe member 14 terminates within and at the bottom of a pocket or box member 18 inset with respect to the engine casing 16 and having an opening 19 to the outside. An upper pipe member 20 passes through the top 21 of the pocket or box member 18, across the latter, and telescopes with the lower pipe member 14. Each upper pipe member 20 has an appropriate offset piping connection 22 with respect to a piston to be cooled so that the inlet and outlet upper pipe members 20 may move with the piston.

The telescopic joint between the lower and upper pipe members 14 and 20 is packed to prevent leakage of water along the outside of the upper pipe member 20. To this end, I show a depending sleeve member 23 extending within the lower pipe member 14 and having an upper flange 24 adapted to be secured to the bottom 25 of the pocket or casing 18 by suitable screws 26. The casing construction 23 surrounds the upper pipe member 20 and it is provided with a

lower inwardly projecting flange 27 to support packing 28, the latter being compressed to the requisite degree of tightness by a gland nut structure at 30. From Fig. 3, 5 it will be noted that the packing 28 is of such a character as to offer great resistance to the passage of water upwardly and outside of the upper pipe member 20.

As the telescopic piping connection is arranged within the engine casing, the upper pipe member 20 passes through the top 21 of the pocket or chamber 18 within the engine casing. It is essential to prevent even a thin film of water adhering to the upper pipe member 20 if contamination of engine oil is to be avoided. To this end, I show a novel form of packing which is capable of maintaining a tight joint with respect to an upper pipe member in a very durable manner. This packing construction includes a tubular member 31 surrounding the upper pipe member 20 and having a ball member 32 fitting a spherical seat 33 in a lower cover member 34 secured to the top member 21. 10 An upper cover member 35 is provided with a socket 36, which mates with the socket 33 and fits the ball portion 32, the cover members 34 and 35 being secured together in any suitable manner, as by the screws 37. 15 The lower cover member 34 is preferably provided with a cylindrical recess 38 to receive a cylindrical follower portion 39 carried by the upper cover member 35, packing 40 of any suitable type being arranged 20 within the recess 38 and held with the proper degree of tightness by the follower portion 39 against the exterior of the ball portion 32. The lower end of the tubular member 31 is connected to a packing housing 40', 25 which contains packing 41 of any suitable type held with the requisite degree of tightness against the upper tubular member 20 by means of a lower gland nut 42, the packing abutting against an upper, inwardly-projecting annular shoulder 43 carried by the housing 41.

From the structure just described, it will be apparent that the packing 41 may be accurately centered with respect to an upper pipe member 20 without likelihood of such packing being worn in an eccentric manner by the reciprocatory motion of the upper piping member. This result is largely due to the fact that the packing 41 is arranged 50 at a considerable distance from the ball-and-socket supporting connection for the tubular member 31, whereby only small lateral pressures are necessary in order to obtain concentric adjustment of the packing with respect to an upper piping member 20.

In operation, cooling water enters a piston 12 through the supply connection 13 and is discharged through the connection 13a. The passage of water upwardly and outside of the upper piping member 20 is

largely prevented by packing 28 surrounding the upper piping member 20 and supported by the bottom of the pocket or box member 18. Experience shows that, however well made such packing may be, it is nevertheless very difficult to prevent the passage of a thin film of water along with the piping member 20 during this upward movement. Accordingly, therefore, I provide an upper packing 41 arranged about the upper pipe member 20 and having a universal supporting connection with respect to the top of the pocket or box structure 18, such packing being suspended from the ball member of the joint by a tubular structure so that only slight lateral forces are necessary to secure proper adjustment of the packing to assume a relation concentric with the tubular member 20, whereby durability of the packing is greatly enhanced. 70 75 80 85

From the foregoing, it will be apparent that I have provided a telescopic type of piping connection which assures the prevention of cooling water for an engine piston from entering the interior of the engine casing, thereby avoiding the contamination of lubricating oil within the casing. Any films of water adhering to the upper pipe members 20 are, therefore, wiped off by the packing constructions 41, such water and possible traces of oil collecting in the chambers 18 from which the collections may be drained from time to time by opening the drainage openings 44. The packing 41 also serves to prevent leakage of oil from the engine casing to the pocket. The opening 19 provides a window through which the condition of the packing may be observed and through which adjustments of the gland nuts may be made. 90 95 100 105

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims. 110 115

Having thus described the invention what I claim as new and desire to secure by Letters Patent is:

1. In an engine construction, the combination, with a casing for working parts of the engine, of means for conducting cooling fluid to or from a reciprocating part of the engine without leakage of such fluid into the casing comprising a pocket member extending inwardly from said casing and forming a chamber entirely separated from the interior of the casing; a conduit passing into the casing and connected to one wall of the pocket member; a second conduit connected 120 125 130

- to the reciprocatory moving part of the engine, passing through the wall opposed to the first mentioned wall of the pocket member, across the chamber, and telescoping with the first conduit; packing between the conduits; packing between said opposed wall of the pocket member and the second conduit; and drainage means communicating with said pocket.
- 10 2. In an engine construction, the combination, with a casing for working parts of the engine, of means for conducting cooling fluid to or from a reciprocating part of the engine without leakage of such fluid into the casing comprising a pocket member extending inwardly from said casing and forming a chamber entirely separated from the interior of the casing; a vertical conduit depending from the lower wall of the pocket member; a second vertical conduit in telescopic relation to the first conduit, extending across the chamber of the pocket member and through an opening in the upper wall of the latter, and connected to the reciprocatory moving part of the engine; a gland construction secured to the bottom wall of the pocket member, extending into the first conduit, and having a fluid tight fit with respect to the second conduit; a second gland construction arranged above the first gland construction and having a fluid tight fit with respect to the second conduit; means for supporting the second gland construction from the upper wall of said pocket member and said means being adjustable laterally in all directions in order that the second gland construction may be aligned due to lateral pressure of the second conduit; and drainage means communicating with said pocket.
- 15 3. In an engine construction, the combination, with a casing for working parts of the engine, of means for conducting cooling fluid to or from a reciprocatory moving part of the engine without leakage of such fluid into the casing comprising a pocket member extending inwardly from said casing and forming a chamber entirely separated from the interior of the casing, said pocket member having a window through which the interior of the chamber is visible and through which access to the interior of the chamber may be had, a conduit passing into the casing and connected to one wall of the pocket member; a second conduit connected to the reciprocatory moving part of the engine, passing through the wall opposed to the first mentioned wall of the pocket member, across the chamber, and telescoping with the first conduit; a packing construction including a casing member fixed to the first mentioned wall of the pocket member, packing within the casing and engaging the second conduit, and a gland nut adjustable with respect to the casing to compress the packing and accessible from the interior of said chamber; a second packing construction including a casing having a spherical portion at one end fitting a spherical seat provided by the second mentioned wall of said pocket member, the casing surrounding the second conduit and extending inwardly of said chamber toward the first packing construction, packing arranged interiorly of the casing, and a gland nut adjustable with respect to the end of the latter casing opposed to its end having the spherical portion in order to compress the packing and to secure a fluid-tight fit thereof with respect to the second conduit; and drainage means communicating with said pocket.
- 20 4. In a cooling device for an engine, the combination of an engine casing, a chamber protruding within the casing and open exteriorly of the latter, a lower vertical pipe member connected to the bottom of the chamber and communicating with the latter, an upper pipe member passing through the top of the chamber across the latter and telescoping with the lower pipe member, packing carried by the bottom of the chamber and surrounding the upper pipe member, a tubular member surrounding the upper pipe member, a ball and socket joint between the upper end of the tubular member and the top of the chamber, and packing carried by the lower end of the tubular member and surrounding the upper pipe member.
- 25 5. In apparatus of the character described, the combination of a chamber having opposed walls, a member movable through openings in the opposed walls and across the chamber, a packing device cooperating with said movable member and including a supporting member fixed to one of said walls, and a second packing device cooperating with said movable member and including a laterally adjustable supporting member carried by the other of said walls.
- 30 6. In apparatus of the character described, the combination of a chamber having opposed walls, a member movable through openings in the opposed walls and across the chamber, a packing device cooperating with said movable member and including a supporting member fixed to one of said walls, and a second packing device cooperating with said movable member and including a tubular supporting member having a ball and socket connection with respect to the other wall of said chamber.
- 35 In testimony whereof I hereunto affix my signature this 24th day of April, 1924.
- ARTHUR JACKSON WEST.
